UNITED STATES PATENT OFFICE.

BENJAMIN A. SLOCUM, OF BINGHAMTON, NEW YORK, ASSIGNOR TO ANSCO PHOTO-
PRODUCTS, INC., OF BINGHAMTON, NEW YORK.

GROOVING MACHINE.

Application filed April 19, 1926. Serial No. 103,178.

My invention relates generally to a machine for placing grooves in certain materials and is directed primarily to an apparatus for grooving the edges of the protective paper used on photographic film cartridges, such grooves acting as light locks or protection for the edges of the sensitized film wound on the spool with the protective paper. It will be understood however that my improved grooving machine is not limited to this particular use but may be advantageously applied in providing grooves in other materials and for other purposes.

The primary object of my invention is to provide such a grooving machine which is automatic in its operation, which will perform the grooving operation at high speed and which is provided with adequate guiding means for accurately aligning the paper with the grooving means.

A second object is to provide novel grooving rollers through which the paper or other material to be grooved passes.

Other objects and advantages in details of construction and operation will be apparent as the description proceeds, reference being had to the accompanying drawing, wherein like reference numerals indicate like parts.

In the drawing:—

Figure 1 is a side view of my assembled machine.

Figure 2 is an end view of a part thereof taken on the line 2—2 of Figure 1 and looking in the direction of the arrows.

Figure 3 is an end view of the part of the machine taken on the line 3—3 of Figure 1 and looking in the direction of the arrows.

Figure 4 is a detail view of the grooving rollers.

Figure 5 is an enlarged detail, partly in section, of a portion of the winding mechanism.

A base member 1 is provided and supports at one end an upstanding bearing member 2, to which is secured a projecting shaft 3, upon which is mounted a flange roll 4, wound with paper 5, or other material to be grooved. The upper end of the bearing 2 is provided with a pin 6 supporting a weight 7, or other suitable device, hanging over the roll of paper 5 in order that the same will not be unwound too rapidly. A supporting wing 8 is provided on the bracket or bearing 2 and supports at its outer end a pin 9 un-

der which the paper or other material 5 is drawn.

The parts just described are conventional in form and have been illustrated diagrammatically only.

There is provided centrally of the base 1, two upstanding side supports 10, provided with a reinforcing web 11 extending between them. Rotatable shafts 12 and 13 have bearing in the upstanding supports 10. Secured to these shafts are the grooving rollers 14 and 15 which are preferably of heavy metal or other material and have their surfaces highly polished. Adjacent either edge of the roller 14 is a groove 16 into which fits the circular ridges 17 carried by the roller 15. The grooves 16 and the ridges 17 are both V shaped as illustrated clearly in Figure 4, for forming the light lock groove on the film paper. Obviously, however, if other than a V shaped groove is desired in the material, these grooves and ridges of the rollers 14 and 15 may be formed to conform to the desired shape.

The shaft 12 is extended beyond one of the guide supporting members 10, as at 18, and upon this shaft are securely mounted the small and large pulleys 19 and 20 respectively. A belt or other form of driving means may connect the small pulley 19 to an electric motor (not shown) or other source of power as desired whereby the shaft 12 will be rotated. The shaft 12 is provided just inside the left hand supporting member 10 in Figure 2 with a gear 21 which meshes with a gear 22 fixed to the shaft 13, whereby upon rotation of the shaft 12 by means of the pulley 19, the rollers 14 and 15 will be rotated in opposite direction.

The side supporting members 10 are provided with laterally projecting wings 23 between the outer ends of which is supported a polished bar or pin 24 around which passes the paper or other material 5 as it is drawn under the pin 9 and through a slot 25 in the web 11. Also journaled in the wings 23 above the pin 24 and to the rear thereof, is a second pin 26 also smoothly polished and provided with guide flanges 27 (see Figure 3) between which passes the material 5. These flanges 27 guide the material 5 in accurate alignment with the roller 14 around which the material 5 now passes, and is then fed between rollers 14 and 15 at which point the grooving action takes place.

The end of the base 1, opposite the upstanding bearing 2, has another upstanding bearing or support 28, provided with a projecting shaft 29 carrying thereon a spool 30 adjustably aligned with the rollers 14 and 15, as by means of the pin 31 carried by the spool and engaging within the slot 32 longitudinally of the shaft 29. A set screw 33 provides means for adjustably fixing the spool 30 in correct alignment to receive the grooved paper or other material 5 as it comes from the rollers 14 and 15.

Also mounted upon the shaft 29 beyond the upstanding bearing 28 is a pulley member 34 rotatable upon the shaft 29, but prevented against sliding movement thereon in one direction by means of the abutment 35 on the pulley engaging against the surface of the bearing member 36 on the upper end of the supporting bearing or standard 28 (see Figure 2). Also mounted upon the shaft 29 and keyed thereto as at 37 for rotation therewith is a clutch face 38 abutting closely adjacent the clutch face 39 carried by the pulley 34. A washer of leather, fabric or other suitable material 40 encircles the shaft 39 between these clutch faces. The clutch member 38 is prevented from endwise movement on the shaft 29 by means of the lock nut 41 screw threaded thereon, and between which nut and the end of the clutch member 38 is provided a tension spring 42 normally urging the clutch face 31 into engagement with the clutch face 39. A driving belt 43 extends between the large pulley 20 on the shaft 12 and the pulley 34 on the shaft 29.

From the foregoing, it will thus be understood that when the material to be grooved is threaded from the roll 4 under the bar or pin 9, around the pins 24 and 26, and to the rollers 14 and 15, it is started in any suit-

able manner upon the spool 30 on the shaft 29. Upon applying power to the pulley 19, it will be obvious that the rollers 14 and 15 will be rotated and due to the belt connection 43 to the pulley 34 on the shaft 29, the spool 30 will also be rotated to take up the material 5 as it comes from between the rollers 14 and 15. In order to take care of the varying diameter of the spool 30, as the material 5 is wound upon it, the friction clutch or slip connection consisting of the clutch faces 38 and 39 is provided. It will be understood that as the material builds up on the spool 30, the pulley 34 may rotate on the shaft 29 against the friction of the washer 40 and the tension of the spring 42 pressing against the clutch face 38. Normally however the friction between the two clutch faces will be sufficient to rotate the shaft 29 through the pulley 34.

Of course many changes in details of construction and operation from construction shown and described herein may be made without departing from the spirit of my invention. I do not therefore limit myself to the exact form shown other than by the appended claim.

I claim:

A grooving machine comprising a base, a supply spool and a take up spool thereon, rollers on said base between which a strip of material is adapted to pass from one spool to the other, V-shaped grooves in one of said rollers and similarly shaped ribs on the other roller adapted to fit in said grooves whereby V shaped grooves are formed in said material, driving means for said rollers and said take up spool, and a friction clutch between said take up spool and said driving means.

BENJAMIN A. SLOCUM.
